UNITED STATES PATENT OFFICE.

EINAR JOHAN BRING, OF FRANKLIN, PENNSYLVANIA,

FIRE-BOX DOOR.

Application filed April 17, 1920. Serial No. 374,657.

To all whom it may concern:

Be it known that I, EINAR JOHAN BRING, a citizen of the United States, residing at Franklin, in the county of Venango and

5 State of Pennsylvania, have invented certain new and useful Improvements in Fire-Box Doors, of which the following is a specification.

This invention has reference to an improved apparatus of the character specified 10 in which there will be obtained greater efficiency and reliability in operation and economy in operating fluid and in which the maintenance cost as well as the original 15 cost of installation will be substantially reduced as compared with certain other forms in common use.

Another object of this invention is the provision of a device of the character specified 20 in which, should any disturbance occur in the fire box such as results from dropping of the crown sheet or the burning out of a flue, the flow of escaping steam through the door opening, assuming the door had been 25 in open position, would act to force the parts to closed position and thus reliably blow the door shut providing a safety factor of considerable value.

30 A further object of this invention is the provision of a door of the character specified which will have a maximum degree of adaptability to a great number of conditions varying on different engines so that it may be applied not only on any fire box which 35 has a suitable sized fire opening without requiring the relocation or rearrangement of other existing apparatus in common use, but also on fire boxes where the customary forms cannot be applied because of lack of 40 space and similar reasons.

45 A further object of the invention is the provision of a pivotal support at each end of each of the two sections of the door so arranged that the door cannot be blown out by any pressure short of an amount sufficient to break the door in two.

50 Still another object of this invention is the provision of a door of this character in which the opening presented by the door when opened will be substantially the same shape as the aperture in the boiler, and when the door is partially opened, it will present a

horizontal gap or slit in the middle of the door which is the best shape for a supplemental air inlet such as is sometimes desired in operation of such fire boxes. 55

Another advantage of my invention is the provision of a door in which weight is reduced to a minimum and in which the various wearing parts such as are liable to 60 need adjustment or replacement are readily accessible.

Still another object obtained by my invention is the provision of a door for fire boxes which adapts itself very economically 65 and advantageously to the assembly of the parts as a unit for convenient application to the structure of the fire box. This object I attain by making the cylinder and valve in substantially one unitary structure 70 and the frame and door parts in a second unit and arranging the whole so that in assembling the parts, the workman has but to connect the operating rod and tighten the two bolts that hold the cylinder to the frame. 75

Still another advantage incident to my invention is the provision of a mechanism in which a minimum of manual effort will be required to open the door and in which when actuating the parts by hand, it is not 80 necessary to approach the boiler as closely as with other door structures.

In addition to the several advantages above set forth my door has the capacity of 85 operating without being affected by the difference in pressure inside of the fire box and the pressure of the atmosphere outside. In doors commonly used heretofore a substantial difference in pressure between the inside and outside conditions of the fire box sometimes causes the doors to rub against the frames, which creates such friction where the difference in pressure is considerable 90 that it sometimes produces substantial interference with the free actuation of the doors by the piston or other automatic means employed and thus interferes with the successful use of the device. In a door constructed in accordance with my present improvement this difficulty is entirely eliminated because 95 the friction which may be caused by any differences of pressure between the inside and the outside of the fire box will be exerted only upon the door pin whose radius 100

is so small that any substantial disarrangement from such variation of pressure will not be of any consequence with regard to the amount of power required to actuate the parts.

Another object which I obtain by means of this invention is the provision of a door of this general type which requires no more room when open than it does when closed, and in which also because of the small amount of power that is required to actuate the parts, a power device or piston may be used which is not provided with packing rings and in which even after a considerable amount of wear has taken place, the door members will move without substantial difficulty.

The above, as well as such other objects as may hereinafter appear, I obtain by means of a construction which I have illustrated in preferred form in the accompanying drawings, wherein—

Figure 1 is a front elevation of a door embodying my improvement; Figure 2 is a side elevation of the door with a portion of the actuating means shown in section and with a portion of the fire box with its door opening and of the lower door segment in open position shown in dotted lines; Figure 3 is a detail of the actuating mechanism showing a part of it in section on the line 3—3 of Fig. 2; Figure 4 is a perspective view of one of my improved doors with the parts in closed position and Figure 5 is a like perspective view showing the parts in full open position.

Referring now more particularly to Figures 4 and 5, it will be seen that the door proper consists of three principal parts, the door frame 1, the upper door plate 2, and the lower door plate 3, both plates being held in position at either side by pivot pins 4 so that the upper plate may swing freely in an upward direction and the lower plate downwardly as indicated in Figure 5.

In order to secure an action of the doors in unison they are connected together by links 5 and 6 working in association with the rocking lever 7 which is pivoted at 8 so that when the upper door is forced upward either by hand or by the power mechanism with which it is attached, the connecting link 6 will cause the rocker to rotate around its center in a manner to force the connecting link 5 downward to move the lower door plate in unison with the upper plate.

As a great many of the locomotives now in use have sloping boiler heads at the rear, I prefer to make the door plates so that they meet below the center line of the opening which makes the upper plate somewhat larger and heavier than the lower plate. As a result of this difference in size of the two plates when the door is applied on the sloping head referred to and both plates are

opened the outside face of the top plate will be approximately in the same vertical plane with the outside face of the lower plate. This arrangement shortens the distance into the fire box around the lower half of the door opening and thus gives additional clearance for the fireman when he is endeavoring to throw coal into the back of the fire box.

Constructing the upper and lower plates of different sizes as indicated also has the advantage that when the upper plate is larger and heavier than the lower plate it will assist the door to close by gravity and if the differential of weight be made sufficiently large, the door can be made a gravity closing door arranged to be opened manually or by power and closed by gravity.

As a convenient means to hold the door open, I provide a latch 9 and introduce into the upper plate a plurality of notches as indicated at 10 and 11 so that when the latch is dropped down it will catch in these notches or on the lower edge of the upper door plate when it is fully opened and thus I am enabled to hold the door either in fully opened position or at various predetermined partially opened positions such as will serve when the engine is standing at a station for example, to reduce the amount of black smoke or to regulate the condition of combustion in the fire box.

It will also be observed that when the doors are fully opened the lower plate will act as a shovel shield and thereby protect the joint which occurs in most fire boxes between the inner and outer sheet of the fire box construction. The segments actually form or define the opening by virtue of the fact that they telescope or nest into the frame to positions opposite each other. The frame is enlarged at the top and bottom to provide shroud-like portions 1^a and 1^b which cooperate with the segments to cover or close the door opening and receive the segments when opened. The segments may therefore be made acute angled, as shown, which means, among other things, that a maximum size of firing opening or passage may be obtained.

I prefer to construct the door plates 2 and 3 of double or hollow walls with air chamber space between them, the outer air being admitted through suitable apertures 12 and the communication with the interior being obtained by apertures 13 shown in Figure 2 as located in the inner wall 14.

As a convenient means for manually actuating the door, I arrange the handle 15 shown in Figures 1 and 2; this handle being of convenient access to the fireman because of the projection outwardly of the body of the two door plates.

Referring now more particularly to Figures 1, 2 and 5, it will be seen that I have

therein indicated the application to the upper door plate 2 of a lug 16 carrying a threaded pin 17 which engages with the link 18 constructed to form an actuating connection with the threaded pin 19 that is socketed in the piston 20, the pin 19 extending through a slot 19^a in the cylinder 21.

The air supply for actuating the piston 20 comes through the pipe connection 22^a 10 attached in the threaded opening 22 and controlled by the valve 23 which is mounted in a bracket 24 that carries by means of a pin at 25 a rocker lever 26 that receives its motion in turn from a foot treadle 27 or other 15 suitable actuating device.

All of this actuating mechanism is so arranged that when the treadle 27 is pushed down air will be admitted under pressure below the piston 20 and will move the piston 20 upward acting through the link 18 to push upward on the upper door plate 2 and that in turn will operate to open both door plates through the link connections on the other end of the said plates.

While I have shown the actuating mechanism somewhat in detail, my invention is directed primarily to the features of the door itself and other forms of actuating device might be employed for imparting the requisite power to move the door and the particular form of piston and valve and actuating device which I have indicated is not specifically of my invention, on which account it will not be necessary to describe it more in detail herein. If desired reference may be had to the copending application of F. W. Martin, Serial No. 375,042, filed April 19th, 1920 for a detailed description of this operating mechanism.

It will be seen that the structure disclosed provides a door which can probably be best described by the term "clam shell" inasmuch as the movements of the plates or segments are somewhat similar to those of the types of excavating buckets known as "clam shell" buckets and in some of the appended claims I have designated the door as a "clam shell" door in order to distinguish this new class of door from the ordinary doors such as the butterfly and sliding doors.

I claim:

1. A clam shell door for a fire box opening including segments rotatable toward the box to uncover the opening and outwardly to cover the opening.

2. A clam shell door for a fire box opening including segments having their ends pivoted adjacent the box so that the segments rotate toward the box in door opening movement.

3. A clam shell door for a fire box opening including a frame adapted to be applied to the opening and a pair of door segments having their ends pivoted in said frame and adjacent the opening whereby one of said

segments rotates upwardly and inwardly and the other downwardly and inwardly toward the box on door opening movement.

4. A door for a fire box opening including a clam shell segment member pivoted adjacent the box and rotatable toward the latter to uncover the door opening.

5. A clam shell door for a fire box opening including segments rotatable toward the box to uncover the opening and outwardly to cover the opening, means for operating one of the segments, and a connection between segments whereby the operation of one segment actuates the other.

6. A clam shell door for a fire box opening including segments rotatable toward the box to uncover the opening and outwardly to cover the opening, means for operating one of the segments, and a link and lever connection between the segments whereby movement of one segment imparts reverse movement to the other.

7. A clam shell door for a fire box opening including segments rotatable toward the box to uncover the opening and outwardly to cover the opening, the upper segment being heavier and operatively connected with the lower.

8. A clam shell door for a fire box opening including a plurality of door segments and a plurality of shrouds, the segments nesting in the shrouds on rotation to uncover the opening.

9. A clam shell door for a fire box opening including a plurality of door segments and a plurality of shrouds, the segments nesting in the shrouds on rotation to uncover the opening and cooperating with the shrouds to cover the opening when the door is closed.

10. A clam shell door for a fire box opening including a plurality of stationary members and a plurality of rotatable door segment portions, the latter nesting in the former on rotation to uncover the opening and cooperating with the former to cover the opening.

11. A clam shell door for a fire box opening comprising a pair of segments pivoted adjacent the door opening and a shroud cooperating with the segments when the latter are closed to cover the door opening and adapted to receive the segments when the latter opens.

12. A clam shell fire door comprising a frame adapted to be applied to the door opening and provided with an outwardly projecting shroud portion and a pair of segments pivoted adjacent their ends to the frame, the shroud portion cooperating with the segments to close the door opening and to receive the segments on opening movement.

13. A clam shell fire door comprising a frame adapted to be applied to the door

opening and a pair of door segments having their ends pivoted and being adapted to nest within the frame on rotation to uncover the opening.

5. 14. A clam shell door for a fire box opening comprising door segments pivoted adjacent the door opening, and linked together to rotate about an approximately horizontal axis, the upper segment being heavier.
15. 15. A clam shell door for a locomotive fire box opening comprising a pair of pivoted segments adapted to extend into the

opening and to shield the surfaces of the opening when the door is opened.

16. A door for a locomotive fire box opening including a door segment of substantially the shape of the sector of a sphere pivoted on its diameter to swing into the opening and to shield the surfaces of the opening when the door is opened. ¹⁵

In testimony whereof, I have hereunto signed my name.

EINAR JOHAN BRING. ²⁰
